(57) **CLAIM**

The ornamental design for an image detector camera, as shown and described.

DESCRIPTION

FIG. 1 is a front view illustrating our new design for an image detector camera;

FIG. 2 is a rear view of the image detector camera of FIG. 1;

FIG. 3 is a top view of the image detector camera of FIG. 1; FIG. 4 is a bottom view of the image detector camera of FIG. 1;

FIG. 5 is a left side view of the image detector camera of FIG. 1; and,

FIG. 6 is a front perspective view of the image detector camera of FIG. 1.

The portions of the image detector camera illustrated in broken lines in FIGS. 1 and 6 are for illustrative purposes only and form no part of the claimed design.
